US0D1072731S

(12) **United States Design Patent** (10) **Patent No.:** **US D1,072,731 S**
(45) **Date of Patent:** **** Apr. 29, 2025**

(54) **BATTERY DOCK**

(71) Applicant: **DELTA ELECTRONICS, INC.**,
Taoyuan (TW)

(72) Inventors: **Ting-Yun Lu**, Taoyuan (TW); **Yi-Chih Hsu**, Taoyuan (TW); **Jui-Yang Hung**, Taoyuan (TW); **Shih-Hsiu Lee**, Taoyuan (TW); **Ming-Jen Hsu**, Taoyuan (TW)

(73) Assignee: **DELTA ELECTRONICS, INC.**,
Taoyuan (TW)

(**) Term: **15 Years**

(21) Appl. No.: **29/892,254**

(22) Filed: **May 16, 2023**

(30) **Foreign Application Priority Data**

Nov. 18, 2022 (TW) 111305803

(51) **LOC (15) Cl.** **13-02**

(52) **U.S. Cl.**
USPC **D13/107**

(57) **CLAIM**

The ornamental design for a battery dock, as shown and described.

DESCRIPTION

FIG. 1 is a perspective view of a battery dock showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view showing the battery dock in use; and,

FIG. 9 is another perspective view showing the battery dock in use.

The equal length broken lines in the figures depict portions of the battery dock that form no part of the claimed design. The broken lines showing a battery in FIG. 9 depict environmental subject matter that form no part of the claimed design.

1 Claim, 9 Drawing Sheets
